SMOKE DETECTION AND EXTINGUISHING SYSTEM

Albert F. Olsen, Minneapolis, Minn., assignor to
Northwest Airlines, Inc., St. Paul, Minn., a corporation of Minnesota

Application June 28, 1948, Serial No. 35,602

7 Claims. (Cl. 169—2)

1

This invention relates to smoke detecting and fire extinguishing systems adapted to efficiently service and protect a room, compartment or series of compartments from a central point or station.

My improved system is applicable to rooms or compartments in buildings, multi-compartment transportation vehicles, but has particular applicability for airplanes and ships employing numerous closed compartments, bunkers and the like, where fire hazard and attendant dangers are great.

While smoke detection and fire extinguishing systems have been utilized in ships and airplanes, such devices and system, to my knowledge, have not been satisfactory for several reasons. False fire indications were frequent since such systems have depended on visual indicators often affected by dust in the compartments or by alarms responsive to increased temperatures within the compartments. Moreover, many of said systems employed extinguishing fluid-control means which were uncertain in operation, sometimes failing to discharge and sometimes misdirecting the distribution of extinguishing fluid.

In the case of systems using visual indicators, accumulation of frost or condensation in the observation chamber in numerous cases resulted in failure of detection.

An object of my invention is to provide a simple, positively operated system for servicing and protecting one or more compartments or rooms of airplanes, ships, transportation vehicles and buildings which will give to the pilot or attendant at a central station, visually and through sense of smell, a warning by sample of smoke from a predetermined compartment with positively operated fire extinguishing mechanism operative and controllable from the seat or platform at the central station.

A further object is to provide a system of the class described wherein as far as possible, the same elements of the system are utilized for collecting and transmitting smoke from an individual compartment to the particular indication nozzle as well as for transmitting extinguishing fluid under pressure in the opposite direction from a source to the compartment where the fire occurs.

Another object of the invention is the provision of a smell and visual detection system where possible errors as to the location of a fire and application of extinguishing fluid to that point, are eliminated.

It is a further object to provide an adaptation

2

of my invention for a multiplicity of isolated or spaced compartments to selectively and successively test for smoke in each thereof and to selectively distribute extinguisher to anyone thereof in the event of fire.

My multiple compartment system preferably employs a common detector nozzle and source of extinguishing fluid and control therefor but utilizes indicator mechanism and a valve system for injecting, through operation at the central station, extinguishing fluid into the particular compartment where fire has occurred.

These and other objects and advantages of my invention will more fully appear from the following description made in connection with the accompanying drawings wherein like reference characters refer to similar parts throughout the several views and in which:

Fig. 1 is a diagrammatical view showing a simple form of my improved smoke detecting and fire extinguishing system applied to a luggage compartment in the fuselage of a commercial airplane, portions of the plane being indicated by dotted lines and parts of my apparatus being broken away and others shown in section;

Fig. 2 is a detail view showing a longitudinal section of a suitable form of detection nozzle comprising a part of my system;

Fig. 3 is a fragmentary vertical section showing a positively operated mechanism for discharging extinguishing fluid such as carbon dioxide from a container or source and for simultaneously closing a valve to shut off flow of gaseous medium or fluid to said detection nozzle;

Fig. 4 is a diagrammatical perspective view of the fuselage of a large commercial passenger plane with portions thereof broken away and with an embodiment of my system operatively installed therein;

Fig. 5 is an electrical diagram showing the electrical indicating system and valve controls adapted to successively indicate compartments from which samples of gaseous medium are drawn and discharged through my detection nozzle and operative also to, upon detection of fire, selectively connect the particular compartment where the fire has occurred with the extinguishing fluid distributor; and

Fig. 6 is a detail view mostly in vertical section showing the indicator arm with provision of manual operation when the same is desirable.

Referring now to the simplified form of the invention illustrated in Fig. 1 to Fig. 3, my system as shown, is applied to an airplane to service and protect from the cockpit adjacent the pilot's

seat, a luggage compartment removed some distance therefrom. My system includes a combination smoke-withdrawing and extinguishing fluid-distributing member as shown in the form, of a tubular element 18 arranged in rectangular or annular form and provided with a series of spaced and as shown, staggered orifices 19a. Air and smoke or other gaseous media from within the closed compartment C (indicated in dotted lines) is adapted to be drawn through these orifices into the communication conduit 11 of my system. Conduit 11, as shown, extends forwardly from one end of member 18 and is connected at its forward end with an upstanding detector nozzle 12 which as shown, is tapered conically at its extremity to discharge a jet of gaseous medium upwardly, generally in the direction of the head of a pilot or attendant seated in the seat S (indicated by dotted lines) within the cockpit of the plane. Means is associated with the conduit system to withdraw air from compartment C producing a partial vacuum in conduit 11 and causing air or smoke to travel forwardly through nozzle 12. In some installations, differential pressure during flight between the interior cockpit CP and compartment C has been found adequate to produce a flow of air forwardly and upwardly through nozzle 12. I prefer however, to provide a discharge fan 13 mounted in a casing 13a forming an enlargement of the base of nozzle 12 and directing discharge of air tangentially through such nozzle. A motor M, as shown, is mounted exteriorly of the fan casing 13a with its shaft projecting axially into the casing, as illustrated in Fig. 1.

Intermediate of the detection nozzle 12 and combination smoke withdrawing and fluid distributing member 18, I provide a positively operated means for instantly introducing fire extinguishing fluid under pressure into conduit 11 and to cause such fluid to flow rearwardly into the distributing member 18 and to be discharged in spaced jets therefrom into the compartment for extinguishing a fire.

In the form of apparatus illustrated, I provide a container holder in the form of a horizontally disposed supporting bracket 14 mounted as shown, at the base and rear of the pilot seat. This bracket has adjacent its forward end, a compressible seat 14a adapted to engage the discharge end or neck extremity of a conventional type of sealed container X which holds an extinguishing fluid such as carbon dioxide gas, under pressure. Means is provided such as the clamp 15 for forcing the extremity of the container against its seat to form a sealed joint between such parts. Conventional containers of the class described are provided with a penetrable closure disc D which may be pierced to release the fluid under pressure.

At the forward end of bracket 14, I provide an upstanding fitting 16 having a vertical passage 16a therein which is connected with the delivery conduit 11 at its lower end. The upper end of passage 16a is angularly disposed to communicate with the central apertured portion of the compressible seat 14a and has mounted therein and extending axially thereof, a piercing pin 17 slidably mounted in a packing gland 18 seated in the upper and forward portion of fitting 16. Piercing pin 17 terminates at its inner end in a point head normally spaced a slight distance forwardly of the closure disc D of the container. The outer end of the piercing pin 17 in the form of mechanism disclosed extends a short

distance beyond the fitting 16 and is connected by slot and pin connection 19a with the forward and depending arm 19b of an operating lever 19 which, as shown, is intermediately fulcrumed on an upstanding lug 16b integrally formed with the upper portion of fitting 16. The handle portion 19c as shown, extends in normal position rearwardly for convenient reach by the pilot or operator.

I prefer to provide a closure valve 20 actuated by operation of the lever 19 for closing off communication between the nozzle 12 and my system when lever 19 is thrown to puncture disc D and release extinguishing fluid from the container. To this end, a valve casing section 11a is provided in conduit 11 just forwardly of its connection with the passage 16a of fitting 16 and a slide or gate valve 20 affixed to the lower end of a tappet rod 20a is normally held in open position by means of a coil spring 21 interposed between an enlarged or embossed portion of the valve casing and an abutment pin 20 fixed to intermediate portion of the tappet stem. The valve casing 11a is of rectangular internal cross sectional shape and valve 20 is similarly shaped to closely fit the interior thereof when the valve is closed. The upper portion of the tappet stem 20 is guided through a forwardly extending lug 16d integrally formed or otherwise rigidly affixed to fitting 16. The upper extremity of tappet rod 20a is in the form of a tappet head which is engaged by the curved camming edge 19d provided by the lower end 19b of the operating lever, the relation of said camming edge to the pivot 22 of lever 19 being such that in the swinging of the lever, valve 20 will be moved downwardly to close the passage in the valve casing 11a.

To materially assist visual detection of smoke issuing from nozzle 12, I prefer to provide the interior of this nozzle with a small light source such as a very small incandescent electrical bulb 23 mounted within a suitable miniature socket 24 which is mounted laterally in the upper portion of nozzle 12, a short distance below the conical discharge end thereof.

Operation

It will of course, be understood that while in Figs. 1 to 3 I have illustrated a single application of my system to protect and service one compartment, that this identical simplified system may be duplicated for each of a number of compartments with the individual detection nozzles 12 for each system disposed in upstanding, close spaced relation, all directed upwardly towards the side of the head of the pilot or operator, so that smoke discharged will be readily visible and accessible for smell.

Air is constantly withdrawn from the compartment serviced through the smoke withdrawing member 18 and communicating conduit 11, such withdrawn air or gaseous media issuing from the orifice of nozzle 12 and being directed upwardly at the side of or before the face of the person seated or stationed in the position of seat S. In this connection, I find it desirable to employ a fan of sufficient power to place the interior of chamber C under slight partial vacuum and thereby, minimize leakage and content of combustion supporting air in that compartment.

If smoke is produced in compartment C, it will almost immediately be drawn through my system issuing from nozzle 12 and being directed forcibly upward in jet form in proximity to the pilot's

nostrils. The pungent odor will immediately be detected and further visual detection is of course present, materially aided by the production of light in the issuing jet of smoke. Thus, if the central station or cockpit is in darkness, the smoke may be readily observed as well as smelled by the operator.

Where the system is multiplied for serving a number of compartments, the operator will first be warned of smoke probably through swelling the same and may quickly determine the precise nozzle from which that smoke is issuing since the nozzles are all uncovered and are provided with lights on the inferior thereof.

To extinguish the fire in a predetermined compartment, the pilot or operator merely reaches back and pulls the operating lever 19 forwardly, the piercing pin 17 penetrating the closure disc D of the container and causing carbon dioxide or other extinguishing fluid under pressure, to be immediately released. Simultaneously to release of extinguishing fluid, the valve 20 is cammed to closed position, breaking off communication between the nozzle 12 and the forward portion of conduit 11 ahead of the communicating fitting 16. The released extinguishing fluid under its pressure is discharged rearwardly through conduit 11 into the distributor head 10 where it emanates in the form of the invention shown, through a multiplicity of orifices and is distributed throughout the upper portion of the compartments serviced.

With my structure, if it is necessary to supply an additional extinguishing fluid container to fully extinguish a fire, the substitution may be made with ease and speed by merely slipping the container X from its resilient retaining means after retracting lever 19 rearwardly to normal position and pushing the new container into place.

The escape and expansion of extinguishing fluid through the fitting 16a and the large amount of heat absorption there produced, enables the pilot or attendant to readily know that the extinguishing operation is being carried on and subsequent warming of the line and fitting 16 makes clear to the pilot by sense of touch, that the extinguishing fluid is spent.

In Figs. 4 to 6, I illustrate in diagram, the modification of my invention applied to selectively detect and extinguish fire in a plurality of different compartments by successively extracting samples of gaseous medium from the compartments and discharging the same through a common detection nozzle and for selectively connecting any particular compartment where a fire has occurred with the extinguishing fluid distributor.

To this end, in Fig. 4 a large commercial transport fuselage is shown, broken away to indicate the pilot's cockpit CP and storage compartments C1, C2 and C3, each of these storage compartments being provided with a combination smoke-withdrawing and fluid distributing member 10, as shown, of annular form similar to the member 10 previously described. Each of said members 10 are connected by an independent conduit 11 with a valve casing V disposed preferably at a point behind the pilot's cockpit. The several valve casings V (3 in number in the embodiment shown) are disposed in close spaced relation and individually communicate at their upper ends with a manifold duct 30 which extends forwardly to communicate with an upstanding smoke-detecting nozzle 12 common to all the conduits 11 and similar in construction to the smoke-detecting

nozzle previously described, with reference to the form of the invention shown in Figs. 1 to 3. The common detecting nozzle 12 is provided at its base with a fan casing portion 13a having mounted therein, a fan 13 which is driven by a motor M, all of similar construction and function to the similar parts of the form of the invention first described.

Intermediately of nozzle 12 and the three valves 10 V, manifold duct 30 is supplied with a common available source of extinguishing fluid and operating mechanism and valve mechanism for immediately and easily rendering this extinguishing fluid available and in discharge with the manifold duct 30. The structure of the holder and retainer for the fluid tank X, the fitting for communication with the discharge end of the container, the lever actuated operating or seal-piercing mechanism and the simultaneously operating valve structure in manifold duct 30, as shown, are all identical with the similar structure shown in Figs. 1 to 3 and previously described with reference to the first form of the invention.

My system illustrated and diagrammed in Figs. 4 to 6 includes an electrically or time actuated system for progressively and in sequence, opening and closing the three valves V1, V2 and V3 (see Fig. 5) whereby samples of air withdrawn from the three compartments serviced will be successively taken at short intervals and discharged through the common smoke detecting nozzle 12 at a point readily visible to the pilot or attendant and readily accessible for smell.

While various mechanisms can be utilized to accomplish this purpose and successively operate at short intervals, the valves V1, V2 and V3, I illustrate an electrical system selectively controlled by an electric clock mechanism, indicated as an entirety by the letters EM, having as shown, three sets of wiping contacts 1, 2 and 3, which are engaged by the normally moving contact arm and handle 31 of the electric clock. The valves in valve casings V are preferably of the solenoid type, normally urged to closed position by gravity or spring action and each is equipped with an electro-magnetic coil (not shown) which is, when energized, adapted to lift the plunger thereof to open selectively, the valves for short intervals. The electrical system or circuit diagrammed in Fig. 5 is equipped with a master switch MS which may be opened to render the electric clock mechanism inactive, but which does not affect the electrical system 55 for controlling opening and closing of the several valves V1 to V3 respectively.

The movable contact arm 31 provided with a dielectric handle 31a may be manually turned to cause simultaneous wiping of the two corresponding, arcuate, stationary contacts for the three sets of solenoid valves. Thus, to very definitely determine the compartment from which smoke is issuing, the pilot or attendant may retain the movable contact 31 momentarily in the positions 1, 2 or 3, where apparently, indication of fire was obtained and if the movable contact is wrongly positioned, smoke will no longer emanate from detection nozzle 12. As soon as the compartment from which smoke issues is very definitely determined, the movable contact arm 31 is lifted in the appropriate position, master switch MS is opened and the particular valve V1, V2 or V3, as the case may be, remains open for communication of the particular smoke-withdrawing and fluid-distributing member 10

with the manifold duct 30. The pilot or attendant then pulls forward on the operating lever 19, causing the sealed end of the extinguishing fluid container X to be punctured and simultaneously closing the valve 20 to prevent forward passage of extinguishing fluid to the nozzle 12. The discharged fluid under great pressure, is transmitted through the common duct 30 to the particular conduit 11 servicing the compartment in which the fire has been started. After the fire has been extinguished and the empty container replaced, the system may again readily be put in operation by closing the master switch MS which controls the operation of the electric clock mechanism.

To enable the rotary and manually settable contact arm 31 to be adjusted at will, I provide a suitable means such as a retractable ratchet connection 32a between the arbor shaft 32 of the electrical clock mechanism and a stub shaft 33 slidably housed and journaled in a bearing collar 34. Stub shaft 33 is affixed non-rotatively to the handle 31a and rotary contact member 31 and extends through the stationary dial 35 on which the stationary, arcuate contacts are mounted. A coil spring 36 urges stub shaft 33 inwardly to normally connect the movable contact member and handle with the shaft 32 of the electric clock mechanism. With such mechanism, the movable contact may be manually disconnected from driving engagement with the electric clock during operation of the latter and may be manually adjusted during operation of the clock or when the electric clock is idle, to energize selectively, electromagnetic coils of any one of the solenoid valve mechanisms V1, V2 or V3. The electrical diagram of Fig. 5 also shows the motor M connected in circuit and provided with a motor switch 37 which may independently cut off operation of the motor even though the electric clock mechanism is in operation.

With the form of my invention illustrated and diagrammed in Figs. 4 to 6 inclusive, a plurality of compartments or rooms may be serviced with provision for rapid interval smoke detection selectively, of the several compartments and with provision for selective application of extinguishing fluid to any one of the compartments, all with the utilization of a minimum number of parts, mechanisms and cooperating elements.

It will, of course, be understood that various changes may be made in the form, details, arrangement and proportions of the parts without departing from the scope of my invention.

What I claim is:

1. A smoke-detecting and fire-extinguishing system comprising a conduit having a terminal adapted for communication with a closed compartment, an uncased smoke detection nozzle having a jet-directing orifice, a small conduit connected to said nozzle and constructed to support said nozzle to direct a small jet of gaseous medium adjacent the nostrils of a person positioned at a central station such as an airplane cockpit, means for connecting said nozzle with said conduit, means for normally causing a flow of gaseous medium from said terminal through said conduit and through said nozzle, means for introducing fire-extinguishing fluid under pressure into said conduit and for simultaneously shutting off flow of gaseous medium through said nozzle, said means having an operating element mounted adjacent the nozzle conduit.

2. In a smoke-detecting and fire-extinguishing system utilizing a combination smoke-withdraw-

- ing and fluid-distributing member adapted for disposition in a compartment, an elongated, small, smoke-detection element having an end orifice adapted to direct a small jet of gaseous medium 5 adjacent the nostrils of a person positioned at a central station, a conduit connecting said nozzle with said smoke-withdrawing and fluid-distributing member, means for causing normally, a flow of gaseous medium from said smoke-withdrawing and fluid-distributing element through said nozzle, means for introducing fire extinguishing fluid under pressure into said conduit between said nozzle and said fluid distributing member and a valve for shutting off flow of gaseous medium 15 through said nozzle and an operating member mounted adjacent said smoke-detection element and having connections for simultaneously operating said fluid-introducing means and for closing said valve.
- 20 3. In smoke-detecting and fire-extinguishing apparatus, a conduit system adapted to both withdraw gaseous medium from a compartment and to supply extinguishing fluid to such compartment, a nozzle connected with said conduit 25 system at a remote point from a compartment to be serviced, said nozzle terminating in a tapered discharge end adapted to be directed towards the face of an operator and adapted to discharge a jet of gaseous medium, means for normally 30 setting up a flow of gaseous medium in the direction of said nozzle and a small light-source within said nozzle inwardly of the discharge thereof to illuminate and apply refraction to smoke issuing from said discharge.
- 35 4. Detection and control mechanism for a smoke-detecting and fire-extinguishing system of the type utilizing a fluid-distributing member disposed in a remote compartment and having connection with a conduit for transmitting smoke 40 from said compartment as well as for conducting extinguishing fluid to said compartment, a small, elongated smoke-detection nozzle having an orifice at its outer end and provided with base attachment means to position said nozzle for directing a small jet of gaseous medium adjacent 45 the nostrils of a person in predetermined position at a station such as the cockpit of an airplane, said nozzle having means for connection with the main conduit of said system, a holder 50 for a container of extinguishing fluid mounted adjacent the base of said nozzle in position for control and inspection by the pilot or other operator, mechanism associated with said holder for instantly releasing the contents of said fluid-extinguishing container into the main conduit of 55 said system and for simultaneously shutting off communication of said nozzle with said system.
5. Detection and fluid supply and control mechanism for a smoke-detecting and fire-extinguishing system of the type utilizing a fluid-distributing and smoke-receiving member disposed in a remote compartment and a main conduit in communication therewith, said mechanism comprising a compact supporting structure 60 adapted to be fixedly mounted adjacent a pilot or operator's seat located in a central station such as the airplane cockpit, a visual smoke-detection element supported in upstanding relation from said supporting structure, said supporting structure 65 adapted to be fixedly mounted adjacent a pilot or operator's seat located in a central station such as the airplane cockpit, a visual smoke-detection element supported in upstanding relation from said supporting structure, said supporting structure including a passage-forming medium communicating with said detection element and adapted for coupling with the main conduit of said system, a holder mounted on said supporting structure for retaining a container of extinguishing fluid, means associated with said holder for 70 75

connecting the discharge of a held container with a passage-forming medium supplied by said supporting structure and an operating member mounted on said holder and disposed adjacent said supporting structure for instantly connecting the interior of a held container with said last mentioned passage.

6. The structure set forth in claim 5, a valve in said passage-forming medium and an actuating connection between said operating member and said valve to cause closing of said valve when extinguishing fluid is released from a held container.

7. Detection and fluid supply and control mechanism for a smoke-detecting and fire-extinguishing system of the type utilizing a combined fluid-distributing and smoke-receiving member disposed in a remote compartment and a main conduit in communication therewith, said mechanism comprising a small, elongated smoke-detection nozzle having an orifice at its outer end and provided with base attachment means to position said nozzle for directing a small jet of gaseous medium adjacent the eyes and nostrils of a person in predetermined position at a station such as a cockpit of an airplane, said nozzle hav-

5
10

ing means for connection with the main conduit of said system, a holder and fluid-release structure for a container of extinguishing fluid adapted for mounting adjacent the base attachment means of said nozzle in position for control and inspection by feel by the pilot or other operator, said structure having a fluid-discharge passage for connection with the main conduit of the system and having fluid-release mechanism and an operating member mounted on said structure to instantly actuate said mechanism at the control of the operator and adjacent said smoke-detection nozzle.

ALBERT F. OLSEN.
